UNITED STATES PATENT OFFICE.

ROY J. COOK, OF CHICAGO, ILLINOIS, ASSIGNOR TO GEORGE C. MURRAY, OF CHICAGO, ILLINOIS.

FRictional DRAFT GEAR.

Application filed December 30, 1918. Serial No. 268,942.

To all whom it may concern:

Be it known that I, Roy J. Cook, a citizen of the United States, residing at Chicago, in the county of Cook and State of Illinois, have invented certain new and useful Improvements in Frictional Draft Gears, of which the following is a specification.

This invention relates to draft gears for railway cars and the like, and its purpose is to provide an improved form of friction draft gear comprising an improved construction and arrangement of the frictional gripping elements. The principal object of the invention is to provide a friction draft gear having a large number of frictional gripping surfaces, whereby the apparatus operates more efficiently than friction draft gears of the kind heretofore employed.

Other objects and advantages of the invention will appear from the following specification taken with the accompanying drawings in which one embodiment is illustrated.

In the drawings—

Figure 1 shows a top plan view of my improved draft gear illustrating a portion thereof in horizontal section on the line 1—1 of Fig. 2;

Fig. 2 shows a transverse sectional view taken on the line 2—2 of Fig. 1;

Fig. 3 shows a perspective view of one of the casings in which the friction blocks and other elements are mounted;

Fig. 4 shows a side elevation of the draft gear with the lower part thereof illustrated in vertical section on the line 4—4 of Fig. 2;

Fig. 5 shows a perspective view of one of the friction blocks;

Fig. 6 shows a perspective view of another friction block;

Fig. 7 shows a perspective view of a third form of friction block which is surrounded by the form of block illustrated in Fig. 6.

In the drawings, the draft gear is illustrated as being mounted in the usual manner between the parallel draft sills 10 which have the draft lugs 11 secured thereto by rivets 12. The draft rigging is supported by the carrier bars 13 which extend between the draft sills and are secured to the lower flanges thereof, these draft sills being of channel form, as illustrated in Fig. 2. The draft rigging comprises a draft yoke 15 which is rigidly connected by rivets 16 to

the butt 17^a of the coupler 17. The lower arm of the draft yoke 15 rests in the depressions or channels 18^a of the carrier bars 13, as shown in Fig. 2.

The friction draft rigging is carried by the yoke 15 and it comprises two box-like casings 18 of the form shown particularly in Fig. 3. These casings are arranged to face toward each other within the yoke, the rear wall 19 of one casing seating against the rear face of the coupler butt 17^a and engaging the shoulders of the forward draft lugs 11, while the rear wall 19 of the other casing seats against the rear wall of the yoke 15 and engages the shoulders of the rear draft lugs 11. Each casing 18 comprises parallel upper and lower walls 20 and 21, respectively, which are formed integrally with the outwardly diverging vertical walls 22. Reinforcing ribs 23 extend from each of the inclined walls 22 to the rear wall 19, and the upper and lower walls are provided with openings 24. The inclined faces of the walls 22 are adapted to coact with the friction blocks 25 which are of the form illustrated in Fig. 5, and having a zig-zag cross-section longitudinally thereof, so that each lug comprises two diverging central walls 25^a and oppositely directed inclined end walls 25^b. In the embodiment illustrated, the angle between the walls 25^a is substantially the same as the angle between the walls 25^a and 25^b, and this may preferably be about one hundred and thirty degrees. Reinforcing ribs 25^c extend between each of the parts 25^a and the adjacent part 25^b. The inner surfaces of the converging walls 25^a of the block 25 are adapted to coact with the walls 26^a of other friction blocks 26 which are mounted centrally between the blocks 25 and which have other surfaces 26^b inclined with respect to the surfaces 26^a and adapted to coact with the surfaces of the central friction block 27 which is substantially diamond-shaped in cross-section, as shown in Figs. 1 and 7. The blocks 26 are provided with three frictional sides, including the surfaces 26^c, which coact with the spring caps 29. These spring caps are mounted within the casings 18 and seat against the coil springs 30 which abut at their other ends against the inner surfaces of the rear walls 19 of the casings 18. The spring caps 29 are provided with lugs or dowel pins 29^a 110

which extend into the springs to prevent displacement thereof, and the rear walls 19 are provided with other dowel pins 19^a adapted to extend into the springs at their 5 other ends.

The blocks 26 are provided with notches 26^e which are adapted to engage the strengthening ribs 25^c of the blocks 25 when the members 26 are pushed outwardly by 10 the compression of the draft gear. It will be seen that portions of each of the blocks 25, 26 and 27 rest upon the lower walls 21 of the casings 18, which lower walls extend beyond the forward edges of the 15 inclined walls 22, so that all parts of the draft rigging are self-supporting within the yoke.

It will be observed that each of the two 20 friction blocks 25 have two surfaces coacting with corresponding surfaces on the walls 22 of the casings 18 and each of these blocks 25 is further provided with two centrally converging surfaces which coact with the surfaces 26^a of the blocks 26. Each of the 25 blocks 26 is provided with another surface 26^b which coacts with one of the surfaces of the central block 27, and in addition each of the blocks 26 has a friction surface 26^c engaging one of the spring caps 29, 30 so that a very large number of contacting surfaces are provided for furnishing a frictional resistance to the compression of the draft gear.

When the draw-bar 17 is moved rearwardly, the forward casing 18 is carried rearwardly by the direct engagement therewith of the coupler butt, and, at the same time, the engagement of the walls 22 of the forward casing with the walls 25^b of the 35 intermediate blocks 25 serve to push the blocks 25 inwardly and rearwardly as these blocks ride on the walls 22 of the rear casings 18. At the same time, the intermediate friction blocks 26 are forced against the central block 27 and are thus caused to separate as they move outwardly on the wedge blocks 25 toward the ends of the yoke. This movement forces the spring caps 29 and the 40 walls 19 of the casings 18 toward each other and results in the compression of the springs 30. When the draw-bar 17 is pulled in a forward direction, the rear casing 18 is moved in a forward direction by the direct engagement therewith of the rear wall of the yoke and the friction blocks are operated in the 45 manner previously described, but in the opposite direction, since in this case the forward casing 18 remains stationary against the forward draft lugs 11.

Although I have shown and described a single embodiment of the invention for purposes of illustration, it will be understood that it may be constructed in various different forms without departing from the 50 scope of the appended claims.

What I claim is:

1. The combination in a draft gear of a yoke, a pair of casings mounted within said yoke and having oppositely disposed outwardly inclined side flanges, side friction 70 blocks supported by said casings and having inclined surfaces adapted to coact with said flanges, said side friction blocks being integrally formed and being each provided with a pair of inwardly converging surfaces located longitudinally of the draft gear between said first-named surfaces, intermediate wedge blocks located between said side wedge blocks and coacting therewith, and spring mechanism located between said intermediate wedge blocks and said casings. 75 80

2. The combination in a draft gear of a yoke, a pair of casings mounted within said yoke and having oppositely disposed inclined flanges which diverge outwardly in 85 pairs, a pair of integral one piece side friction blocks extending between said casings and having surfaces coacting with said flanges, said side friction blocks converging inwardly toward each other between said 90 casings and between said surfaces which coact with said flanges, and intermediate friction blocks coacting with the inwardly converging parts of said side friction blocks.

3. The combination in a draft gear of 95 two casings adapted to be mounted in opposite ends of a yoke, each of said casings having a pair of diverging flanges, friction blocks supported by said casings and coacting with said flanges, intermediate friction 100 blocks located between and coacting with said first-named friction blocks, spring caps having friction surfaces extending transversely of the yoke and adapted to coact with opposite sides of said intermediate 105 friction blocks, and springs extending between said caps and said casings.

4. The combination in a draft gear of a pair of casings provided with oppositely disposed diverging flanges, side wedge blocks 110 extending between said casings and coacting with said flanges, intermediate wedge blocks located between and coacting with said side wedge blocks, spring caps frictionally engaging said intermediate wedge 115 blocks, and springs extending between said spring caps and said casings.

5. The combination in a draft gear, of 120 two casings each having oppositely disposed diverging frictional surfaces, friction blocks extending between and coacting with the oppositely disposed frictional surfaces of said casings, said friction blocks having intermediate converging friction surfaces, intermediate friction blocks coacting with said 125 last-named frictional surfaces of said first-named friction blocks, a central wedge block interposed between and coacting with said intermediate friction blocks, plates coacting with said intermediate friction blocks, and 130

springs interposed between said plates and the end walls of said casings.

6. The combination in a draft gear, of two oppositely disposed pairs of frictional flanges inclined with respect to the longitudinal axis of the draft gear, friction blocks extending between and coacting with said frictional flanges of opposite pairs, said friction blocks having intermediate converging surfaces, intermediate friction blocks of irregular cross-section coacting with said intermediate frictional surfaces of said first-named friction blocks, spring caps engaging opposite sides of a plurality of said intermediate friction blocks, springs engaging said spring caps, and means for holding the other ends of said springs in fixed relation with respect to said first-mentioned frictional flanges.
- 20 7. The combination in a draft gear, of two oppositely disposed pairs of frictional flanges inclined with respect to the longitudinal axis of the draft gear, friction blocks extending between and coacting with said frictional flanges, said friction blocks having intermediate converging surfaces, a plurality of intermediate friction blocks each having an inclined surface to coact with one of the converging intermediate surfaces of said first-named friction blocks, a central friction block having two pairs of surfaces
- 25
- 30

each inclined to the longitudinal axis of said draft gear and adapted to coact with similarly inclined surfaces on said intermediate friction blocks, and compression devices engaging opposite end faces of said intermediate friction blocks.

8. The combination in a draft gear, of two oppositely disposed pairs of frictional flanges inclined with respect to the longitudinal axis of the draft gear, friction blocks extending between and coacting with said frictional flanges, said friction blocks having intermediate converging surfaces, a plurality of intermediate friction blocks each having an inclined surface to coact with one of the converging intermediate surfaces of said first-named friction blocks, a central friction block having two pairs of surfaces each inclined to the longitudinal axis of said draft gear and adapted to coact with similarly inclined surfaces on said intermediate friction blocks, said intermediate friction blocks having other surfaces lying in planes normal to the longitudinal axis of said draft gear, spring caps engaging said last named surfaces of said intermediate friction blocks, and springs coacting with said spring caps.

In testimony whereof, I have subscribed my name.

ROY J. COOK.
